UNITED STATES PATENT OFFICE.

JOHN MARMORSTEIN, OF JERSEY CITY, NEW JERSEY.

ANTISLIP ATTACHMENT FOR SHOE-HEELS.

1,290,768.

Specification of Letters Patent.

Patented Jan. 7, 1919.

Application filed June 21, 1918. Serial No. 241,186.

To all whom it may concern:

Be it known that I, JOHN MARMORSTEIN, a citizen of the United States, residing at Jersey City, in the county of Hudson and State 5 of New Jersey, have invented certain new and useful Improvements in Antislip Attachments for Shoe-Heels; and I do hereby declare the following to be a full, clear, and exact description of the invention, such as 10 will enable others skilled in the art to which it appertains to make and use the same.

My invention relates to an anti-slip attachment for shoe heels, and the novel features thereof are hereinafter described, illustrated in the accompanying drawings, and embraced within the scope of the appended 15 claims.

In said drawings,

Figure 1 is a perspective view showing the 20 device attached to a shoe heel,

Fig. 2 is a plan view of the device removed,

Fig. 3 is a transverse sectional view taken along lines 3—3 of Fig. 2,

Fig. 4 is a top plan view of a slight modification of the invention, and

Fig. 5 is a transverse sectional view taken along lines 5—5 of Fig. 4.

Referring more particularly to the drawings, 5 designates a band of sheet metal having its major portion 6 bent to conform to the contour of the outer curved surface of a shoe heel, or in other words, is of substantially U-shape, while the lesser portions 7 or extremities are deflected at right-angles to the portion 6 and are overlapped, the same occupying a position immediately in advance of the front portion of the heel. Disposed transversely of this band, considered 30 in its entirety, is a heel supporting member, 8, it being essential that this member should occupy a position between the top and bottom edges of the band 5.

In the modification illustrated in Figs. 4 45 and 5 of the drawings, the heel support 9 extends inwardly from the wall of the band 5 and both the heel support and the band are preferably cast as an integral structure.

Each of the forms may be attached in two 50 ways. Firstly, as shown in Fig. 1, a small

wing screw, or the equivalent, as 10, is combined with a lace or strap 11, the end of the fastening device 10 being brought into engagement with the adjacent front portion of the heel, and the lace, which is attached to 55 opposite sides of the portion 6, being carried forward over the instep and tied as at 12. Secondly, the lace 12 may be dispensed with, and a pair of winged screws 13 positioned toward the rear of portion 6 for frictional engagement with the outer surface of the heel.

As will be seen from the foregoing explanation, my invention may be manufactured at a low cost; may be expeditiously attached and detached; and when worn, the downwardly protruding portion of the band 5 will effectively engage ice or other slippery surfaces and thereby resist any tendency toward slipping.

What is claimed is:

1. An anti-slip attachment for shoe heels, comprising an integral band of sheet metal bent to form a substantially U-shaped portion conforming to the contour of the outer surface of a shoe heel, the extremities of said band being bent at substantially right-angles to said U-shaped portion and lying in overlapping relation along the front of the heel, a heel support having opposite ends joined 75 to the rear of the U-shaped portion and to the overlapped extremities, and means for securing both portions to the heel.

2. An anti-slip attachment for shoe heels, comprising an integral band of sheet metal 85 bent to form a substantially U-shaped portion conforming to the contour of the outer surface of a shoe heel, the extremities of said band being bent at substantially right-angles to said U-shaped portion and lying 90 in overlapping relation along the front of the heel, a heel support having opposite ends joined to the rear of the U-shaped portion and to the overlapped extremities, and a fastening device extending through the 95 overlapped extremities of said band and the adjacent portion of said heel support.

In testimony whereof I affix my signature.

JOHN MARMORSTEIN.
